UNITED STATES PATENT OFFICE.

MELVILLE I. KEIM, OF CHICAGO, ILLINOIS.

TOBACCO-BOX.

1,216,135.

Specification of Letters Patent. Patented Feb. 13, 1917.

Application filed December 11, 1915. Serial No. 66,312.

To all whom it may concern:

Be it known that I, MELVILLE I. KEIM, a citizen of the United States, residing at Chicago, in the county of Cook and State of Illinois, have invented a certain new and useful Improvement in Tobacco-Boxes, of which the following is a specification.

My invention relates to tobacco boxes and the general object of the invention is to provide a box of convenient size and shape to be held in the hand and stored in the pocket and capable of readily delivering tobacco to a pipe or to the cigarette paper for rolling cigarettes. Boxes of this nature are not broadly new, but it is my purpose to provide a construction in which, by pressing a button, a delivery spout is opened and the contents are at the same time agitated in such a manner as to avoid compressing the tobacco and yet agitating it and loosening it sufficiently to insure its sliding out through the spout. It is my purpose, also, in a combination of this character to provide an open throat or passageway to and through the spout so as to avoid any obstructing of the passage.

I accomplish my object by the mechanism illustrated in the accompanying drawings, in which—

Figure 1 is a perspective view of a tobacco box embodying my invention and having a portion of the side broken away to reveal the internal parts.

Fig. 2 is a perspective view of the back end of the box showing the slide for covering the receiving opening.

Fig. 3 is a longitudinal sectional view of the box showing the internal mechanism.

Similar numerals refer to similar parts throughout the several views.

The box itself has two parallel sides 1, rounded at the front. The top, bottom, front and back are formed preferably of a single strip 2 of metal following the contour of the sides. At the back there is an opening 3, through which the box may be filled and this opening is closed by means of a slide 4. At the forward end of the bottom is a delivery opening 5 at the rear end of which is a spout which is attached by means of a hinge 6. This spout consists of a floor 7 and two side wings 8 rising therefrom at the lateral edges, the wings being at such distance apart as to lie close to the sides of the delivery opening. The floor of the spout is curved upward at the forward end to conform to the contour of the forward end of the box and to deliver the tobacco more conveniently into the cigarette paper. The spout is operated by means of a yoke formed of two side bars 9 connected by a cross bar 10. By preference this yoke consists of a single flat strip of metal and is pivoted at the lower end of the arms to the upstanding wings 8 of the spout. Rising from the middle of the cross bar 10 is a push rod 11 which passes up through a housing 12 inside of the box and terminates in a button or head 13. A helical spring 14 is located within the housing. The spring encircles the rod and rests upon the bottom of the housing. The upper end of the spring engages the base of the button and normally holds it raised and the delivery spout closed.

In operation, the box will usually be held in the hand of the user in such position that the delivery spout will be downward and the button uppermost, the forefinger resting upon the button. The box will naturally be tilted downward toward the front and this brings the bottom of the box to an incline which assists gravity to move the contents toward the spout, especially when the contents are low. When the box is in this position it is also true that the front inclines rearwardly toward the opening, the curve being at first precipitate and gradually decreasing in pitch. Thus, as most naturally held by the user, the delivery spout will be at the lowermost point of the device and the contents will gravitate toward it from both ends of the box. Now when the button is pressed, it not only causes the spout to open but causes the cross bar 10 to descend and agitate the contents sufficiently to prevent them from packing. It will be noted that the cross bar is some little distance (possibly $\frac{1}{8}$ of an inch) above the spout. Hence, it is never in the way to obstruct the passage of the tobacco out through the spout and yet it is near enough to loosen up the tobacco above the spout. The yoke form is also advantageous because it permits the arms 9 to be arranged at the extreme sides of the spout thereby leaving a free and clear passage for substantially the entire width of the spout. This effectively prevents clogging and permits the tobacco to flow in an even continuous stream for sufficient time to deliver enough tobacco for the ordinary cigarette.

It is evident, also, that in this, the preferred form, the floor of the spout when in open position has a steeper pitch at the inner end than at the delivery end. This permits the 5 tobacco to flow freely from the box until it has completely passed out of the box, after which it is directed more nearly horizontally, thus making it more convenient for spreading the tobacco in the paper.

10 Having thus described my invention what I claim as new and desire to secure by Letters Patent, is:

1. A tobacco box having parallel sides and a bottom provided with a discharge 15 opening, a delivery spout hinged at one end of said opening, and a yoke having side arms attached to said spout and located at a distance apart approximately equal to the full width of the spout, said side arms being 20 connected at the top by a cross bar, and

means connected to said cross bar for operating it and the spout.

2. A tobacco box having parallel sides and a bottom provided with a discharge opening, 25 a delivery spout hinged at one end of said opening, said spout having upstanding wings at the sides, parallel side bars pivoted to said wings and passing up into the box, a cross bar connecting said side arms at the top, said cross bar being located a short distance above the spout, whereby a free passage through the spout is formed and yet the contents of the box may be agitated, and a push rod passing through the top of the box whereby the spout may be swung about 30 its hinge.

In witness whereof, I have hereunto subscribed my name.

MELVILLE I. KEIM.
